[57] CLAIM

The ornamental design for an automobile body, as shown and described.

DESCRIPTION

FIG. 1 is a side view of my new automobile body, it being understood that the opposite side is a mirror image thereof; FIG. 2 is a front view of my new automobile body; FIG. 3 is a rear view of my new automobile body; FIG. 4 is a perspective front view of my new automobile body; and,

FIG. 5 is a perspective rear view of my new automobile body.

The broken lines showing of the automobile's tires is for illustrative purposes only, and forms no part of my claim design.
